UNITED STATES PATENT OFFICE.

GEORGE E. SCHINDLER, OF ASHLAND, WISCONSIN.

ELECTRIC TIME-SWITCH.

1,227,326.

Specification of Letters Patent.

Patented May 22, 1917.

Application filed August 9, 1916. Serial No. 114,081.

To all whom it may concern:

Be it known that I, GEORGE E. SCHINDLER, a citizen of the United States, residing at Ashland, in the county of Ashland and State 5 of Wisconsin, have invented new and useful Improvements in Electric Time-Switches, of which the following is a specification:

This invention relates to a time switch for electric circuits and has for its primary 10 object to provide a device of the character set forth by which a change in time can be accurately accomplished and at the same time insure a good electrical connection.

An object of the invention is to construct 15 a time switch of very few parts in which certain elements can assume various positions corresponding to different periods of time.

Another object of the invention is the 20 novel manner of constructing a track so that the contact elements may be renewed when the same has reached a stage when good electrical contact is not accomplished.

A further object of the invention is to 25 provide a time switch in which the movable elements are so associated as to minimize the resistance to the flow of current.

With these and other objects in view, the 30 invention consists in the construction, combination and arrangement of parts as will be hereinafter more fully described, illustrated in the accompanying drawings and pointed out in the claims hereunto appended.

35 In the drawing:—

Figure 1 is a side elevation of the time switch.

Fig. 2 is a top-plan view thereof.

Fig. 3 is a vertical sectional view.

40 Figs. 4, 5 and 6 are detailed views of the tracks and movable contacts.

Fig. 7 is a diagrammatic view illustrating the wiring.

Referring to the drawings, the numeral 1 45 designates the casing supporting any suitable form of driving element, illustrated diagrammatically at 2. The shaft 3 from the driving element 2 passes through the casing and has secured thereto one end of 50 an arm 4. Supported by the casing concentrically of the shaft 3 is an inner track 5 and an outer track 6 each formed with a T-shaped slot 7. The tracks are similar in construction with the exception that the 55 outer track 6 is parted at the points 8 and 9 and the section thus formed is held in place

by means of springs 11. A plurality of movable contacts 12 are arranged in the slot 7 of the outer track, the combined length of which being equal to the interval of time 60 that the switch is to allow the passage of current.

The arm 4 has secured thereto, a wiper 13 adapted to wipe over the movable contacts 12 but to be spaced from the track 6. Also 65 secured to the arm 4 is a contact 14 continuously engaging the walls of the slot 7 in the inner track 5. The arm 4 is composed of insulating material, and such being the case the wiper 13 is electrically connected to the 70 contact 14 by the conductor 15.

Mounted upon the casing 1 is a pair of switches 16 and 17 the former adapted to directly establish the continuity of the main circuit 18 while the latter is arranged to establish the continuity of the main circuit 75 through the shunt circuit 19 the terminals of which are connected respectively to the inner and outer track.

Take for an example that the time switch 80 is to establish the continuity of the main circuit from 8 p. m. to 1 a. m.; the movable contacts 12 are inserted in the outer track until the distance is bridged between the numeral 8, upon the scale 20 and the numeral 1. Upon the arm 4 reaching a point 85 when the wiper 13 reaches the advance contact 12 current will flow through the main circuit and will continue to do so until the wiper 13 leaves the rear contact 12. 90

From this arrangement it will be seen that in a very simple manner I am able to increase the time that the main circuit 18 is energized in such a manner as to insure a good electrical connection and thus minimize the resistance to the flow of current. 95

From the foregoing description taken in connection with the accompanying drawings the advantage of the construction and the method of operation will be readily apparent to those skilled in the art in which the invention relates and while I have described the principle of operation of the invention together with the device which I now consider to be the best embodiment 100 thereof, I desire to have it understood that the device shown is merely illustrative and that such changes may be made when desired as are within the scope of the claims. 105

What I claim is:—

1. In a time switch, a casing having a circular scale, a circular track mounted on

said casing within said scale and formed with a T-shaped slot, an arm, and contacts shaped to slidably engage the walls of the slot in said track and adapted to engage 5 said arm.

2. In a time switch, a casing having a circular scale, a circular track mounted on said casing within said scale, and formed with a T-shaped slot, an arm, and contacts 10 shaped to slidably engage the walls of the

slot in said track and adapted to engage said arm, a second track, and a contact carried by said arm and continuously engaging the walls of a slot in said second track.

In testimony whereof I affix my signature 15 in presence of two witnesses.

GEORGE E. SCHINDLER.

Witnesses:

H. A. DAVIS,
BLOP FACINICH.
